H. HANDSCHY.
BARLEY SHELLER.

Patented Sept. 5, 1834.

Sept. 5, 1834

Henry Handschy, of Muskingum Co. Ohio 8396X
Letters Patent

The schedule referred to in these Letters Patent and making part of the same, containing a description in the words of the said Henry Handschy himself, of his improvement being a machine for the purpose of shelling barley for cooking and table use -

To all to whom these presents shall come: Be it known that I, Henry Handschy, in the County of Muskingum, in the State of Ohio, have invented a new & useful machine for the purpose of shelling barley for cooking and table use, and that the following is a full description of the construction and operation of said machine, as invented by me -

1st. a square log 11 inches, with mortices 11 inches from centre to centre apart the mortices, to be six inches on the top, 12 inches deep, hollowed in the middle in a pot form, nine inches - 2nd. Two upright posts 10 inches square, 10 feet long, framed into the mortice log - 3rd. two braces, 10 by 4 inches, to be framed in the upright posts 2 feet from the bottom one, and the other 2 feet from the top, with mortices 3/4 inches, corresponding horizontally with the mortices in the bottom log - 4th. Stampers, 10 feet long, 3 inches square, to go in the mortices - 5th. Arms, 13 inches long, 2 by 4, to be morticed in the middle of the Stampers - 6th. two bottom sills, 12 inches square, 8 feet long, on which the above machine is placed, 2 feet from one end.

7th. two posts, 10 inches square, 6 feet long, morticed into the bottom sills 20 inches from the Stampers, with two braces, on each side connecting the two posts together - 8th. a Welbeam 12 inches round, to be placed with quadrant, on the posts centre, level 3 inches below the arms of the Stampers.

9th. Arms in the Welbeam, 13 inches long, 6 by 2, with fork, and rollers, are morticed in the Welbeam, corresponding with the Stampers, four in a square form for each stamper - but where the motion is quick two or three may do - The length depends on the number of actions. I should recommend 10, which will make 16 feet, I started two, may the 10th last, which answers a good purpose which induced me to apply for a Patent. -

1/4
The use of the foregoing machine is to have the barley very dry or kiln dried, to be put in the bottom mortise, in which it is shelled or hulled, but it must occasionally be taken out and separated from the hulk with a cockle sieve; this is as near as can be, the description of the machine as invented by me.
